PACKAGING MACHINE

Paul W. Graw, Yankton, S. Dak.

Application August 26, 1935, Serial No. 37,903

12 Claims. (Cl. 226—129)

My invention relates to packaging machines and has for an object to provide a machine by means of which wooden boxes and particularly wire bound boxes may be readily erected and the contents packed within the same.

An object of the invention resides in providing a packaging machine for use in conjunction with a box having two portions to be drawn together, said packaging machine comprising a stationary 10 abutment and a movable abutment movable toward and from the stationary abutment, said abutments engaging such portions of the box and serving to draw the same together.

Another object of the invention resides in providing a packaging machine including a support, a stationary abutment and a guide extending toward said stationary abutment and in further providing a movable abutment guided for movement by said guide.

20 A still further object of the invention resides in providing a rack movable with said movable abutment and in providing a pinion meshing with said rack for reciprocating said movable abutment.

25 A feature of the invention resides in providing a shaft to which the pinion is attached and in securing to said shaft a drum having a cable wound about the same.

Another object of the invention resides in providing a foot operated lever for operating said cable.

30 An object of the invention resides in constructing said guide from two spaced bars having grooves therein and in forming the movable abutment with an elongated member having tongues 35 slidable within said grooves.

A still further object of the invention resides in arranging said elongated member so that the lower surface thereof is exposed and in attaching said rack to the exposed surface of said elongated member.

40 Another object of the invention resides in constructing the packaging machine with a framework including a main frame rectangular in form and an auxiliary frame also rectangular in form 45 and superimposing said main frame.

An object of the invention resides in providing means at the corners of said frames for supporting said auxiliary frame at any elevation above 50 said main frame.

55 A feature of the invention resides in providing triangular shaped uprights at the corners of the frame having inclined surfaces and in providing lugs on the auxiliary frame for engagement therewith, said inclined surfaces maintaining the

auxiliary frame at various elevations above the main frame.

An object of the invention resides in constructing one or more of said inclined surfaces with notches adapted to receive certain of the lugs on the auxiliary frame.

Another object of the invention resides in providing a table attached to the auxiliary frame for supporting the box, said table being spaced from one of the frame members.

10 An object of the invention resides in constructing said abutments so that the same extend upwardly above the table when at its highest position, one of said abutments being disposed within the space between said table and the adjacent 15 frame member and being movable within said space toward and from the other abutment.

Another object of the invention resides in providing means for rapidly releasing the movable abutment from engagement with the box.

20 Other objects of the invention reside in the novel combination and arrangement of parts and in the details of construction hereinafter illustrated and/or described.

25 In the drawings:

Fig. 1 is a perspective view of a packaging machine illustrating an embodiment of my invention.

Fig. 2 is an elevational sectional view taken 30 on line 2—2 of Fig. 1.

Figs. 3 and 4 are fragmentary elevational sectional views taken on lines 3—3 and 4—4 of Fig. 2.

Fig. 5 is a developed view of a blank from which the box is constructed.

Fig. 6 is a perspective view similar to Fig. 1 of 35 another form of the invention.

Fig. 7 is a plan view of the structure shown in Fig. 6.

Fig. 8 is an inverted plan sectional view taken 40 on line 8—8 of Fig. 6.

Fig. 9 is an elevational cross sectional view taken on line 9—9 of Fig. 6.

Fig. 10 is a fragmentary elevational sectional view taken on line 10—10 of Fig. 7.

45 In the assembling and packing of boxes and particularly wire bound boxes, considerable difficulty and inconvenience has been encountered in supporting the parts while being assembled and in supporting the same during the packing of the box. The present invention forms an extremely simple and practical construction, whereby boxes of such nature may be quickly and conveniently assembled and after being assembled, can be easily and quickly packed and closed.

In order to more fully comprehend the invention, I have shown in Fig. 5 a blank from which a box capable of being erected with my invention is constructed. This blank consists of four panels 9, 10, 11 and 12 which are constructed of 5
ply wood or some other similar material. The panels 9 and 11 form the top and bottom of the box and are identical in construction. These parts have secured to the lateral edges 23 and 24
10 thereof wood cleats 21 and 22 which are of the same length as the width of the box and extend up to the longitudinal edges 25 and 26 of said panels. These panels may be nailed to the said cleats 21 and 22 or secured thereto in any other
15 suitable manner. The panels 10 and 12 are also similar in construction and are of the same width as the panels 9 and 11 and are provided with cleats 15 and 16, which are disposed along the lateral edges 13 and 14 thereof. These cleats
20 are of a length less than the height of the box by twice the thickness of the cleats 21 and 22 so that when the box is assembled the ends of said cleats extend up to the cleats 21 and 22. The four panels 9, 10, 11 and 12 are bound together by two or more lengths of wire 35 and 36
25 which may be single or double stranded and which are secured directly to the cleats and to the panels by staples 37 or otherwise. The arrangement of the panels when the boxes are in
30 knocked down form, is shown in Fig. 5. In the erection of boxes of the kind illustrated, the three panels 10, 11 and 12 are folded into U-shaped form with panels 10 and 11 parallel and panel 11 extending across panels 10 and 11. In
35 such position the two cleats 21 and 22 of panel 11 lie between the ends of the cleats 15, 16 of panels 10 and 11 and the edges 18 of said panels. While in U-shaped form, end panels without cleats are inserted into the interior of the box
40 and placed upon the various cleats. One of the panels rests upon cleats 15 of panels 10 and 12 and upon cleat 21 of panel 11. This panel is nailed to said cleats from the interior of the box. In a similar manner the other end panel is secured to cleats 16 of panels 10 and 12 onto cleat
45 22 of panel 11 by being nailed to said cleats. This leaves the panel 9 hinged to panel 10 and free from the other panels and serving as a cover for the box. After the box has been erected in this
50 manner, the same is filled and the panel 9 swung into position to close the open end thereof. The ends of the two lengths of wire 35 and 36 are next brought together and looped or twisted which securely holds the cover in place and binds the
55 sides of the box to form a rigid and substantial construction.

My invention proper, as shown in Figs. 1, 2, 3 and 4, comprises a framework indicated in its entirety by the reference numeral 38. This 60 framework includes a main frame 39 arranged on an incline which is supported on four legs 41, 42, 43 and 44. The frame 39 comprises side frame members 45 and 46 and end frame members 47 and 48. These frame members are constructed of angle iron and are welded together at the corners. Frame members 45, 46, 47 and 48 have inwardly extending flanges 49 and downwardly extending flanges 50. Legs 41, 42, 43 and 44 are also constructed of angle iron and are 65 welded to said main frame 39 at the corners thereof. These legs lie adjacent the flanges 50 of said angles and are preferably welded directly thereto. The lower ends of the legs 41, 42, 43 and 44 are secured together and braced by means 70 of braces 51, 52, 53 and 54 which may be con-

structed of either bar material or angle iron. These braces are also welded to the legs at the particular localities shown in Figs. 1 and 2.

Superimposing the main frame 39 is an auxiliary frame 55. This frame is rectangular in 5 form, the same as the frame 39, but is slightly narrower and is constructed with side frame members 56 and 57, an intermediate frame member 67 and end frame members 59 and 61. These frame members are constructed from angles 10 which have upwardly extending flanges 62 and inwardly extending flanges 63. The frame members 56, 57, 59 and 61 are welded together at the corners. The frame members 57, 67, 59 and 61 have their flanges arranged so as to form a recess 15 64 extending about the same, as best shown in Fig. 1. In this recess is disposed a table 65 constructed of wood or some other suitable material. This table rests upon the flanges 63 of said frame members. Frame member 67 is spaced from frame member 56 to form an opening 66 through the frame for a purpose to be subsequently more fully described. This causes the table 65 to extend only partly across the frame 55, said table being disposed in close proximity to the frame member 56 and to the right of the auxiliary frame. Secured to the flange 62 of the frame member 61 of frame 55 are two strips of metal 20 68 and 69 which extend upwardly therefrom and which serve as gauges for holding the box to be 25 operated upon in proper position upon the table. Two bars 60 extend across the frame members 56 and 67 and lie flush with the upper surface of the table top 65, these bars serving to support boxes resting upon the table 65 and of a width 30 greater than the width of said table.

For the purpose of supporting the frame 55 upon the framework 38, four uprights 71, 72, 73 and 74 are employed. These uprights are constructed from metal plates and are preferably 40 triangular in form, being provided with inclined edges 75, 76, 77 and 78. These uprights are preferably welded to the flanges 49 of the frame members 45 and 46 and extend upwardly therefrom. The edges 75, 76, 77 and 78 are all parallel 45 with one another and have the same degree of inclination. Secured to the frame members 56 and 57 of the frame 55 are lugs 81 and 82 which are adapted to rest on the respective inclined edges 75, 76, 77 and 78 of uprights 71, 72, 73 and 74. The inclined edges 77 and 78 are constructed serrated as shown in Figs. 1 and 2 to provide notches 83 therein. The lugs 82 are also constructed triangular as shown in Fig. 1 and are adapted to fit into the said notches. By means 50 of this construction the frame 55 can be elevated by sliding the same upwardly along the edges 75 and 76 of uprights 71 and 72 and when the rearward portion of the frame is at the proper elevation the lower portion of the frame can be lowered until the lugs 82 engage the proper notches 83. The table 65 then becomes supported at the 55 desired elevation.

Below the table 65 is a guide indicated in its 60 entirety by the reference numeral 84. This guide consists of two guide bars 85 and 86 which are spaced from one another and which are welded to the flanges 49 of the frame members 45 and 46. The guide bars 85 and 86 have facing grooves 87 and 88 therein and are arranged in spaced 65 relation to form therebetween a slot 89 exposed at both the top and bottom thereof. Within the slot 89 is slidably mounted a slide 91 which is in 70 the form of an elongated bar fitting snugly between the facing surfaces of the guide bars 85 75

and 86. This slide is constructed with tongues 92 at the lateral edges thereof which fit into the grooves 87 and 88 and which cause the said slide to travel in a transverse direction with respect to the frame 39 and at an elevation below the table 65. Slide 91 is formed at one end with an upstanding bracket 93. This bracket has attached to it an arm 94 which extends longitudinally of the frame 39 and which is offset as indicated at 95 and 96 to bring the end portions 291 and 298 of said arm down to the level of the flange 49 of said frame members 45 and 46. The arm 94 has secured to it a number of upwardly extending fingers 97 which are adapted to engage the portions of the box to be brought together, as will be subsequently more fully described. The fingers 97 are of a length such that the same project upwardly beyond the table 65 when in its uppermost position and are disposed within the opening 66 in frame 55. A number of fingers 98 similar to the fingers 97 are secured to the frame member 46 and project upwardly therefrom, said fingers being disposed exteriorly of the frame member 57 of frame 55. Fingers 98 are preferably of the same length as the fingers 97. These various fingers form abutments which engage the sides of the ends of the box and which when the slide 91 is moved toward the right, as viewed in Fig. 1, compress the sides of the box and hold the same in such position while the contents of the box are being packed and the box closed.

For moving the slide 91 along the guide 84, a rack 99 is provided upon the under surface of said slide which is exposed from beneath by virtue of the slot 89 being open at the lowermost portion thereof. The slide 91 may be cast and when cast the rack 99 is cast integral therewith. If desired, however, the slide 91 may be constructed from bar material and in such case the rack is separately constructed and thereafter attached to said bar. Attached to the bar 85 and frame member 50 of frame 39 are two hangers 101 and 102 best shown in Fig. 2. These hangers are preferably welded to the said parts and are drilled at their lower ends to provide bearings 45 which journal a shaft 105. Shaft 105 has attached to it a gear segment or pinion 106 which meshes with the rack 99.

Shaft 105 has attached to it a drum 107 which has secured to it two cables 108 and 109. These cables are wound in grooves 111 formed in the drum 107 and when separately tensioned are adapted to rotate the shaft 105 in opposite directions. Cable 109 has secured to its free end a coil spring 112 which in turn is secured to the frame member 45 of frame 39. Cable 108 passes over a pulley 113 secured to frame member 46 of frame member 39 and extends downwardly therefrom.

Pivoted to the brace 53 of framework 38 is a lever 114. A rivet 115 extends through the end of this lever and frame member and constitutes the pivot for the same. This lever is formed with an offset 116 so that the forward portion thereof is disposed adjacent the leg 43 of framework 38. This lever is adapted to move in a vertical direction about the pivot 115 and has secured to it the end of the cable 108. When the lever 114 is moved downwardly, cable 108 is tensioned and the drum 107 rotated in a clockwise direction, as viewed in Fig. 1. This causes the slide 91 to travel toward the right and abutments 97 thus move toward abutments 98. For operating the lever 114 a pedal 118 is secured to the extreme end 117 of said lever. By exerting pressure upon the pedal 118 as by stepping upon

the same, cable 108 may be drawn downwardly to urge the abutments 97 against the box resting upon the table 65 with sufficient force to hold the sides thereof in place, while the box is being packed. For guiding the lever 114 for direct vertical movement, a keeper 119 is employed which is attached to the brace 54 and the leg 43. This keeper is spaced from the said leg to provide a slot 121 therebetween along which the end 117 of lever 114 travels. By means of this keeper lateral movement of the lever 114 is prevented.

For the purpose of holding the shaft 105 in adjusted position, a ratchet wheel 121 is employed which is attached to said shaft in proximity to the hanger 102. This ratchet wheel is constructed with ratchet teeth 124 adapted to be engaged by a pawl 122. A stud 125 extending through this pawl is secured to the hanger 102 and pivotally holds the pawl so that the same may move into or out of engagement with the teeth 124 of said ratchet wheel. The pawl 122 has pivoted to it an operating rod 126 which passes through the leg 43 and has secured to the end thereof a knob 123. The weight of the pawl 122 causes the same to engage the teeth 124. When the knob is pressed inwardly, pawl 122 is raised and disengaged from the teeth 124, permitting the spring 112 to retract the movable abutment back to normal position.

The use of the invention is as follows: Table 65 is first elevated to a height such that the distance between the ends of the abutments 98 and the table 65 is equal to or slightly less than the height of the box to be handled on the machine. After the box is erected and the five walls thereof are in place, the box is set upon the table 65 with the open portion extending upwardly and with one of its ends resting against one or both of the ledges 69 and 68. The foot is next applied to the pedal 118 which tensions cable 108 and causes clockwise rotation of the shaft 105. This rotates pinion 106 which in turn causes reciprocation of the slide 91 along guide 84. This brings about movement of the abutments 97 toward the abutments 98. When the abutments engage the sides of the box, the same are moved or drawn together a sufficient amount to prevent bulging of the sides when the box is packed. By means of the ratchet 121 and the pawl 122, the shaft 105 is held in adjusted position.

As soon as proper adjustment is procured, the pressure is released from the pedal 118 and the operator is free to pack the box. Packing of the box now proceeds and when packed the cover of the box is applied. The ends of the wires 35 and 36 are next twisted together or looped and the packing operations are completed. When wire bound wooden boxes are used the cleats 21 and 22 of the top 9 of the box straddle the two ends of the box the same as the cleats 21 and 22 of the panel 11. The pressure of the contents of the box usually forces the ends against said cleats and holds the end structure of the box firmly in position. When the wires have been fastened the abutments 97 are released by exerting pressure on the button 123. This moves the dog out of engagement with the teeth 124 of ratchet 121 and permits the spring 112 to rotate the drum 107 in a counter-clockwise direction and return the abutments 97 to the position shown in Fig. 1. The box may then be removed and the operation repeated on another box.

Although I have described my invention as usable in conjunction with wire bound wooden

75

boxes, it can also be comprehended that the same may be used in conjunction with paper boxes or any other type of box in which it is desired to hold the walls of the box from bulging while 5 the same is being filled or packed and a closure is being applied thereto.

In Figs. 6 to 10 inclusive, I have shown another form of my invention which may be used for erecting a wire bound wooden box such as 10 illustrated in Fig. 5. The device comprises a framework 131 which consists of a frame 132 supported on legs 133, 134, 135 and 136. Frame 132 comprises longitudinal frame members 137 and 138 and transverse frame members 141 and 142. 15 These frame members are constructed of angle iron having downwardly extending flanges 143 and horizontally extending flanges 144, said frame members being mitered and welded together at the corners. The legs 133, 134, 135 20 and 136 are also constructed of angle iron and are received within the flanges 143 of frame 132 and welded to the flanges 143 thereof. The framework 131 also includes braces 145, 146, 147 and 148 which are welded to legs 133, 134, 25 135 and 136 at localities best shown in Figs. 6 and 9.

Secured to the flanges 144 of frame 132 is a table 149 which is coextensive in area with the said frame 142. This table may be bolted or 30 otherwise secured to the flanges 144 of said frame. Secured to the one end of the table 149 is an abutment 151 which is stationary with respect to said table. Another abutment 152 carried by said table is movable toward and from 35 the abutment 151 and is moved by a mechanism now to be described in detail.

The abutment 151 is preferably secured to the table 149 by means of screws or otherwise. For the purpose of illustration the said abutment has 40 been shown as attached to one end of the table 149 though it can readily be comprehended that the same may be attached at any locality with respect thereto. When exceedingly short boxes are to be handled in the machine, the movement of the movable abutment 152 may not be sufficient to bring the parts of the box together. In such case, abutment 151 can be moved closer to the abutment 152.

Extending across the two frame members 137 50 and 138 is a transverse guide 153 which consists of two spaced guide bars 154 and 155. These guide bars are formed with a slot 156 therebetween in which a slide 157 is slidable. The guide bars 154 and 155 have transverse grooves 158 55 therein while the slide 157 has tongues 159 formed thereon which slide in said grooves. Slide 157 has attached to it an abutment 161 similar to the abutment 151 which is arranged at right angles thereto. All of the abutments 60 151, 152 and 161 are constructed of angle iron and are formed with flanges 163 resting upon the surface of the table 149 and with other flanges 164 extending upwardly therefrom and which engage the portions of the box disposed 65 upon the table 149.

Extending between the guide 153 and the frame member 142 of frame 132 is another guide 165. This guide comprises two guide bars 166 and 167 identical with the guide bars 154 and 70 155 which are spaced from one another to provide a slot 168 therebetween and which are formed with facing grooves 169. These bars are secured to the frame member 142 and are welded to the guide bar 155 of guide 153. Slidable in slot 168 is a slide 171 identical with slide 157

which is constructed with tongues 172 slidable in the grooves 169. The abutment 152 is directly secured to the exposed upper surface of the slide 171 and is adapted to be moved toward the stationary abutment 151 upon movement of the 5 slide 171 in guide 165.

For the purpose of sliding slide 171 in slot 168, the said slide is constructed upon the under surface thereof with a rack 173. A shaft 174 extending transversely beneath the frame 132 has 10 attached to it a gear segment or pinion 175 which meshes with the rack 173. This shaft is journaled in bearings 176 and 177 which are welded to the longitudinal frame members 137 and 138. Cotter pins 179 extending through said 15 shaft hold the shaft from longitudinal movement with respect to said bearings. Adjacent the gear 175 on shaft 174 is attached a drum 181. This drum has secured to it two cables 182 and 183 20 which are wrapped about a groove 184 formed in said drum. The cable 182 has secured to the free end a tension coil spring 185 which in turn is secured to the frame member 141 of frame 132. Cable 183 extends downwardly and is operated by a device to be presently described in detail. 25 When the cable 183 is tensioned, shaft 174 is rotated in a counter-clockwise direction which causes abutment 152 to travel toward the abutment 151.

Attached to the brace 148 of framework 131 30 is a bracket 186 which has pivoted to it a lever 187. This lever extends below the brace 147 and forwardly thereof. The forward portion 188 of the lever 187 has attached to it a pedal 189 by means of which the said lever may be 35 depressed. The free end of cable 183 is attached to lever 187 and when pressure is exerted upon the pedal 189 the shaft 174 is rotated and the abutment 152 caused to travel toward the abutment 151. For the purpose of guiding the forward end of lever 188 for vertical movement, two 40 guide bars 191 and 192 are employed which are secured to the brace 147 in spaced relation to provide a slot 193 therebetween and along which the portion 188 of lever 187 may travel. The 45 lower ends of the bars 191 and 192 are connected together by means of a tie rod 194 which is welded thereto and which is welded to the leg 136 of the framework 131.

The abutment 161 may be moved laterally 50 along the guide 153 by means of a construction best shown in Fig. 9. On the underside of the slide 157 is a boss 195 which is threaded to receive a screw 196. Screw 196 passes through the flanges 143 of frame members 137 and 138 55 of frame 132 and is held from endwise movement with respect thereto by means of cotter pins 197 passing through said screw. One end of the screw 196 projects outwardly beyond the frame member 137 for a considerable distance and is bent to form a crank indicated by the reference numeral 198. By rotating this crank, screw 196 is screwed in the threaded boss 195 and slide 157 caused to move along the guide 156. This adjusts the position of the abutment 161 with respect to the table 149 and permits of placing said abutment at any locality transversely thereof and of holding it in such adjusted position.

The manner of using the construction shown in Figs. 6 to 10 inclusive is as follows: A box blank 8 such as shown in Fig. 5 is first folded up into U-shaped form by bending the wires 35 and 36 at the localities where the edges 18 and 25 of panels 10 and 11 meet and where the edges 18 and 26 of panels 11 and 12 meet. The 70 75

box is then set upon the table 149 with the panel 10 adjacent the abutment 151 and panel 11 adjacent the abutment 161 and with the edges 13 and 23 of said panels resting upon the table 149. 5 Abutment 161 may be adjusted by means of the screw 196 so as to hold the box in proper position upon the table 149 to permit of easily manipulating the machine and applying the end panels to the same. When the parts of the box 10 are so positioned one of the end panels 7 of the box is inserted into the box and laid upon the cleats 15 of panels 10 and 12 and upon cleat 21 of panel 11. With the parts of the box so positioned, pressure is exerted upon the pedal 189 15 which moves abutment 152 toward abutment 151. This forces the two panels 10 and 12 against the end panel 7 and holds the said panels in such position. While the panels are so held the end panel may be nailed to the cleats 15 and 21. 20 After the said end panel is attached the box is inverted and the same procedure utilized for securing the other end panel 7 to the cleats 16 and 22. This completes the operation of assembling the box and the box is then ready to be packed. 25 If desired, the box may be packed by hand or the same may be mounted in the form of the invention shown in Figs. 1 to 4 and packed as previously explained.

My invention is highly meritorious and provides 30 a construction whereby considerable time may be saved in the erection of wire bound wooden boxes and in the packing of such boxes and other types of boxes as well. The invention is exceedingly simple and practical in construction. By 35 means of the particular mechanism employed, uniform travel of the movable abutment toward the stationary abutment is procured so that regardless of the size of the box the same pressure can be applied to the portions of the box to be 40 drawn together. The stationary abutments may be attached to the table on which they are supported at any locality with respect thereto so that all sizes and types of boxes may be easily handled and manipulated. There are no complicated or 45 intricate parts of the invention to get out of order and packaging machines constructed in accordance with my invention will last for an exceedingly great length of time. My invention is 50 exceedingly simple to operate and adjustments of the parts of the same can be readily made without inconvenience.

Changes in the specific form of my invention, as herein disclosed, may be made within the scope of what is claimed without departing from the 55 spirit of my invention.

Having described my invention, what I claim as new and desire to protect by Letters Patent is:

1. In a packaging machine, a support for a box having two portions to be drawn together, a stationary abutment at one side of the support for engagement with one of said portions, a guide extending across said support in the direction of said stationary abutment, a movable abutment guided by said guide for movement toward and from said stationary abutment and adapted to engage the other portion of the box, a rack movable with said movable abutment, a shaft rotatably mounted with respect to said support, a pinion carried by said shaft and meshing with 60 said rack, a drum carried by said shaft, a cable fixed relative to said drum and encircling the same and a lever pivoted to said support and connected to said cable for operating said shaft to move the movable abutment toward the fixed 65 abutment.

2. In a packaging machine, a support for a box having two portions to be drawn together, a stationary abutment at one side of the support for engagement with one of said portions, a guide extending across said support in the direction of 5 said stationary abutment, a movable abutment including an elongated member guided by said guide for guiding said movable abutment for movement toward and from said stationary abutment whereby the movable abutment can engage the other portion of the box and draw the portions of the box together, a rack connected to said elongated member, a shaft disposed below the supporting surface of said support, a pinion disposed below the supporting surface of said support, a shaft secured to said shaft and meshing with said rack, and manually operated means for rotating said shaft.

3. In a packaging machine, a support for a box having two portions to be drawn together, a stationary abutment at one side of the support for engagement with one of said portions, a guide extending across said support in the direction of 20 said stationary abutment, said guide having a slot extending through the same and a way formed 25 along said slot, a movable abutment having an elongated member guided for movement along said way and exposed from beneath through said slot, a rack on the exposed portion of said elongated member, a pinion meshing with said rack 30 and disposed below said guide, and manually operated means for rotating said pinion.

4. In a packaging machine, a support for a box having two portions to be drawn together, a stationary abutment at one side of the support 35 for engagement with one of said portions, a guide extending across said support in the direction of said stationary abutment, said guide having a slot extending through the same, a way formed along said slot, a movable abutment having an 40 elongated member guided for movement along said way and exposed from beneath through said slot, a rack on the exposed portion of said elongated member, a shaft disposed below said guide and rotatable relative to said support, a pinion 45 on said shaft meshing with said rack, a drum carried by said shaft, a cable fixed relative to said drum and encircling the same, and a lever pivoted to said support and connected to said cable for operating said shaft to move the movable abutment toward the fixed 50 abutment.

5. In a packaging machine, a support, a stationary abutment carried by said support, said support including two spaced bars, said bars having facing grooves therein, an elongated member formed with tongues slidably in said grooves and exposed upon the underside thereof, a movable support carried by said elongated member, a rack on the exposed underside of said support, a pinion disposed below said support and rotatable relative thereto, said pinion meshing with said rack, and manually operated means for rotating said pinion.

6. In a packaging machine, a support including legs, a main frame carried by said legs and a lower frame member connected to said legs, a stationary abutment carried by said main frame, a guide carried by said main frame and extending toward said stationary abutment, an elongated member guided for movement along said guide and exposed upon the under surface thereof, a movable abutment carried by said elongated member, a rack secured to said elongated member upon the underside thereof, a shaft, bearings secured to said main frame for journaling said shaft, a pinion carried by said shaft and meshing 65 70 75

with said rack, a drum secured to said shaft, a lever pivoted to said lower frame member, and a cable fixed relative to said drum and encircling the same, said cable being secured to said lever.

5 7. In a packaging machine, a frame work including a main frame, an auxiliary frame movable in an up and down direction with respect to said main frame, a support for a box having two portions to be drawn together, said support being carried by said auxiliary frame, a stationary abutment carried by the main frame, a movable abutment carried by the main frame and movable toward and from the stationary abutment, said abutments extending above the support at the highest position thereof, said support having an opening therein through which said movable abutment extends, and means for moving said movable abutment toward said stationary abutment.

10 8. In a packaging machine, a framework including a main rectangular frame, uprights at the corners of said frame, an auxiliary rectangular frame disposed within said uprights, members on said auxiliary frame for adjustably supporting said auxiliary frame on said uprights to maintain said auxiliary frame at predetermined elevations, a support on said auxiliary frame for a box having two portions to be drawn together, a stationary abutment on said main frame, a movable abutment on said main frame movable toward and from the stationary abutment, both of said abutments extending above the supporting surface of said support, and manually operated means for urging said movable abutment toward said stationary abutment to draw said portions of the box together.

15 9. In a packaging machine, a framework including a main rectangular frame, uprights at the corners of said frame, said uprights being formed with inclined edges, an auxiliary rectangular frame disposed within said uprights, a support on said auxiliary frame for a box having two portions to be drawn together, lugs on said auxiliary frame for engagement with the inclined edges of said uprights to hold the auxiliary frame at predetermined elevations, some of said uprights having notches therein for the reception of said lugs, a stationary abutment carried by said main frame, a movable abutment carried by said main frame and movable toward and from the stationary abutment, said abutments issuing above the supporting surface of said support, and manually operated means for urging said movable abutment toward said stationary abutment to draw said portions of the box together.

20 10. In a packaging machine, a framework including a main rectangular frame, triangular shaped uprights secured to said frame at the corners thereof and having parallel inclined edges, the edges of some of said uprights being constructed with notches, an auxiliary rectangular frame disposed between said uprights, lugs formed on said auxiliary frame and engaging the inclined surfaces of said uprights, certain of said lugs being receivable within said notches to hold the auxiliary frame in adjusted position with respect to the main frame, a table carried by said auxiliary frame and extending partly

across the same to leave an opening in said frame, a guide extending transversely across said main frame, an elongated member guided for movement along said guide, an abutment secured to said main frame at one end of said guide, an abutment secured to said elongated member, said abutments extending above the supporting surface of said table when the table is at its highest position, the abutment on said elongated member being disposed in said opening in the auxiliary frame, and manually operated means for sliding said movable abutment toward said stationary abutment.

25 11. In a packaging machine, a framework including a main frame having parallel side and end frame members, triangular shaped plate-like uprights secured to said side frame members at the corners of the frame and being formed with inclined edges, some of said uprights having notches in the inclined edges thereof, an auxiliary frame disposed between said uprights and comprising side and end frame members, lugs on said side members of the auxiliary frame for engagement with the inclined edges of said uprights, some of said lugs being received within the notches of said uprights to hold the auxiliary frame in adjusted position, a table carried by said auxiliary frame and extending between said end frame members and being disposed adjacent one side frame member and spaced from the other side frame member, a guide extending transversely between the side frame members of said main frame, an elongated member slideable along said guide, an abutment carried by one of the side frame members of the main frame, an abutment carried by said elongated member, said abutments extending above the surface of said table when at its highest elevation, the abutment secured to said elongated member extending through the space between the spaced side member of the auxiliary frame and the table, and manually operated means for urging said movable abutment toward said stationary abutment.

30 12. In a packaging machine, a support for a box having two portions to be drawn together, a stationary abutment at one side of the support for engagement with one of said portions, a guide extending across said support in the direction of said stationary abutment, a movable abutment guided by said guide for movement toward and from said stationary abutment and adapted to engage the other portion of the box, a rack movable with said movable abutment, a shaft rotatable with respect to said support, a pinion on said shaft meshing with said rack, a drum on said shaft, a ratchet wheel on said shaft, a cable fixed relative to said drum and wound about the same, a lever for operating said cable, a second cable fixed relative to said drum and wound about said drum in the opposite direction, a spring fixed at one end relative to said support and secured to said second named cable, a pawl pivoted relative to said support and engaging said ratchet wheel, and manually operated means carried by said support for moving said pawl out of engagement with said ratchet wheel.
